UNITED STATES PATENT OFFICE.

WILLIAM S. EDSALL, OF BOSTON, MASSACHUSETTS. ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRICAL GENERATING AND DISTRIBUTION SYSTEM AND APPARATUS THEREFOR.

Application filed November 28, 1924. Serial No. 752,781.

To all whom it may concern:

Be it known that I, WILLIAM S. EDSALL, a citizen of the United States, residing at Boston, in the county of Suffolk and State 5 of Massachusetts, have invented an Improvement in Electrical Generating and Distribution Systems and Apparatus Therefor, of which the following is a specification.

This invention relates to electric power- 10 generating and distributing systems and translating and protective apparatus therefor.

An electric switch such as is used on a large generating and distributing system 15 usually comprises an enclosing casing adapted to contain oil or other liquid in which the circuit-interrupting arc is formed, and a gas space above the oil in which the gases formed upon circuit-interruption may expand. Such liquids as oil, and the vapors 20 thereof, are usually combustible in air and, when the circuit is interrupted under heavy load, the arc gases generated may form a combustible mixture with the air in the 25 gas space and, under certain and frequently- encountered conditions, explode, and do damage to the switch and surrounding objects.

A transformer or other electrical apparatus 30 may be subject to similar troubles when the insulation, for some reason, breaks down and an arc forms beneath the surface of the liquid in which the apparatus is immersed.

It has been proposed, heretofore, to maintain the gas space of the switch or transformer filled with an inert gas, or one which 35 does not form a combustible mixture with the insulating fluid within the casing of the electrical apparatus; the supply of inert gas being contained in exchangeable reservoirs of limited capacity. If an inert gas is relied upon to prevent explosions in the casing, a constant supply of the gas must 40 be available and the difficulty experienced, heretofore, of maintaining the gas space of the casing full of inert gas at all times, and the uncertainty thereof, due to leaks in the casing, have, up to this invention, 45 been barriers in the path of commercial use of the inert gas filled casing.

In electric generating plants where steam

is used to operate the prime movers, a large and unfailing supply of inert gas is always available for filling and maintaining filled 55 the gas spaces of the switches and transformers in the plant; and the inert gas is automatically and unavoidably produced in the generation of steam by the combustion of fuel in the steam boiler furnaces. 60 The products of combustion of fuel, as coal, are mainly carbon dioxide and nitrogen, both of which are inert as regards their ability to support combustion; and the remaining constituents of the waste furnace 65 gases are so low in combustible gases as to be negligible.

It is an object of this invention, therefore, to utilize the waste furnace gases, or the inert gases resulting from the combustion of fuel, and circulate them through the gas space of an electric switch, transformer or other electrical apparatus, whereby to exclude harmful quantities of air therefrom and thereby prevent the formation of explosion mixtures within the casing of the 75 apparatus.

It is a further object of this invention to provide means to cool the initially hot products of combustion and remove dust and 80 water vapor and other undesirable products before passing the gases into the casing of the electrical apparatus.

A further object is generally to improve the construction and operation of electric 85 power generating systems and apparatus accessory thereto.

Fig. 1 is a diagrammatic representation of a system embodying this invention.

Fig. 2 is a modified diagrammatic view 90 illustrating particularly a modified manner of effecting an automatic circulation of products of combustion through the gas space in the casing of an electrical apparatus.

As here shown the electric generating 95 plant with which my invention is concerned may have a steam boiler 10 in which steam is generated by the burning of fuel, as coal, in the boiler furnace 12, and the partially cooled, although yet relatively hot, products 100 of combustion may pass through the boiler header 14 into the lower end of a stack 16, and flow upwardly in said stack, due to the draft created by the hot column of gases.

therein, and ultimately pass into the atmosphere. The products of combustion, or the waste furnace gases, are composed mainly of carbon dioxide, nitrogen and water vapor, together with such small amounts of carbon monoxide and free oxygen as to be negligible so far as regards their ability to form a combustible mixture with the oil vapor present in the switch or transformer casing.

10 The steam generated in the boiler may be used to drive the turbine 18 which, in turn, may drive the generator 20, and the current from said generator may pass into a transformer 22 and thence into a line 24, although 15 the particular method of using the steam is not herein of consequence.

I have herein shown an electrical apparatus comprising an oil-immersed electric switch associated with the system and 20 adapted to be maintained filled with the inert products of combustion. The switch comprises the casing 26 adapted to be filled to some level $a-a$ with oil or some other arc-quenching liquid which may be combustible in air but not in the products of combustion. A gas expansion space 28 is provided above the oil level and beneath the cover 30. Stationary switch members 32 extend through the casing and terminate, at 30 their lower extremities, in contact members 34 immersed in the oil; and a movable switch member 36 is also immersed in the oil and is adapted to bridge the contact members.

35 The switch may be included in the line 24 extended from the transformer 22.

As previously stated, when the circuit through the switch is broken under heavy load, gases and vapors may be, and usually 40 are, generated from the oil and rise into the gas expansion space and unit with the air ordinarily contained therein to form a combustible mixture therewith.

In accordance with this invention, I circulate inert products of combustion from the boiler furnace 12 through the gas expansion space whereby to exclude air from said space and thereby prevent the formation of a combustible mixture.

50 To this end, I may provide a conduit 40 which is in communication with the boiler header 14 at one end and with one side of the gas space of the switch casing at the other end and so arranged that products of combustion will flow continually for so long as fuel is burned, from the header into the gas space. If desired, a butterfly valve 42 may be interposed in said header between its connection with said conduit 40 and the 55 stack, whereby to divert a portion of the products of combustion to flow into said conduit. If desired, the flow of products of combustion into and along said conduit may be assisted by the blower 44.

60 While I may merely maintain the gas

space of the switch filled with inert gases, and introduce fresh inert gas in amounts sufficient merely to compensate for losses due to leakage from the switch, I prefer to circulate inert gas in substantial amounts continuously through the casing and thereby guard against dilution of the gases with air and also to sweep out the fixed gases generated from the oil during circuit interruption.

For this purpose, I provide a second conduit 75

46 which is in communication with the gas space of the casing opposite the entrance for the products of combustion, whereby to ensure a thorough sweeping of the gas space with the inert gases. Said conduit 46 may terminate at 47 and discharge into the atmosphere but I prefer to extend it to the stack and discharge the gases therein.

For certain purposes, I may place the conduit 40 in direct communication with the 85 lower end of the stack, and the conduit 46 with the upper portion of the stack, as illustrated in Fig. 2 or connect both conduits with the stack so that a pressure difference exists between them. As thus arranged, a circulation of inert products of combustion will take place automatically through the switch in the direction of the arrows, as the draft is greater in the bottom portion than in the upper portion of the stack.

90 Said conduit 40 is preferably relatively large so that the products of combustion may flow at a relatively slow velocity to the switch, and the cinders and dust therein may settle to the bottom of the conduit; or a dust catching device 48 may be interposed in said conduit to clean the gases passing therethrough. Preferably, also, said conduit is relatively long and has heat-dissipating side walls which act to cool the inert products of combustion, and condense water vapor therein, so that the gas may be cool and free from moisture, as well as clean as it passes through the switch.

100 As thus arranged, an abundant supply of inert gas is constantly available for circulation through the switch or other electrical apparatus and for the reason that the boilers must necessarily be continuously fired in order to maintain electric energy in the distribution system.

I claim:

1. The method of maintaining an inert atmosphere in a casing containing an electrical apparatus, which consists in burning fuel 110 and passing the products of combustion into the casing.

2. A casing containing an electrical apparatus, a body of combustible fluid in which said apparatus is immersed, and gases resulting from the combustion of material other than said combustible fluid above said fluid body.

125 3. The method of maintaining an inert atmosphere in a casing containing an elec-

trical apparatus, which consists in burning fuel and circulating the products of combustion through the casing.

4. The method of maintaining an inert atmosphere in a casing containing a liquid combustible with air and an electrical apparatus immersed in the liquid, which method consists in burning fuel and conducting the gaseous products of combustion into the casing to occupy the space above the liquid therein.

5. The method of maintaining an inert atmosphere in a casing containing a liquid combustible with air and an electrical apparatus immersed in the fluid, which method consists in burning fuel and circulating the gaseous products of combustion through the casing above the liquid therein.

6. The method of maintaining an inert atmosphere in a casing containing a liquid combustible with air and an electrical apparatus immersed in the liquid, which method consists in burning fuel, cooling the products of combustion and conducting the cooled products of combustion into the casing to occupy the space above the liquid therein.

7. The method of maintaining an inert atmosphere in a casing containing a liquid combustible with air and an electrical apparatus immersed in the liquid, which method consists in burning fuel, cooling and cleaning the products of combustion and conducting the cooled and cleaned products of combustion into the casing to occupy the space above the liquid therein.

8. The method of preventing explosions in a casing containing a liquid combustible in air and an electrical apparatus immersed in the liquid, which method consists in burning fuel and conducting the gaseous products of combustion into the casing to occupy the space above the liquid and to exclude air from said space.

9. The method of preventing explosions in a casing containing a liquid combustible in air and an electrical apparatus immersed in the liquid, which method consists in maintaining a supply of gaseous products of fuel combustion in the casing to occupy the space above the liquid therein and to exclude air from said space.

10. The method of preventing explosions in a casing containing a liquid combustible in air and an electrical apparatus immersed in the liquid, which method consists in burning fuel in a continuous manner and circulating the gaseous products of combustion continually through the space in the casing above the liquid therein.

11. The combination of a casing containing a liquid combustible in air and an electrical apparatus immersed in the liquid, a

fuel-burning furnace, and means to conduct the products of combustion from said furnace into said casing.

65

12. The combination of a casing, an electrical apparatus contained in said casing, a fuel-burning furnace, and means to conduct the products of combustion from said furnace into said casing.

70

13. The combination of a casing, an electrical apparatus contained in said casing, a fuel-burning furnace, a stack adapted to receive the products of combustion from said furnace, and means to circulate a portion of the products of combustion from said furnace through said casing and then to conduct them into said stack.

75

14. An electric generating and distributing system having the combination of a steam-generator, a fuel-burning furnace therefor, a stack adapted to receive the products of combustion of said furnace, a casing, an electrical apparatus contained in said casing, and means to circulate a portion of the products of combustion from said furnace through said casing and then to conduct them into said stack.

80

15. The combination of a conduit through which gaseous products of combustion are adapted to flow, a casing, an electrical apparatus contained in said casing, and means to by-pass a portion of the products of combustion in said conduit through said casing.

85

16. The combination of a casing containing a liquid combustible in air and an electrical apparatus immersed in the liquid, and means to maintain an inert atmosphere in the casing above the liquid including a generator of gases inert with respect to the liquid, and means to conduct said gases into said casing to occupy the space above the liquid therein.

95

17. The combination of an electric switch having a casing adapted to contain a combustible arc-quenching liquid and a gas-expansion space above the liquid, relatively separable switch-members immersed in the liquid, a fuel-burning furnace, and means to direct the products of combustion from said furnace into the gas expansion space of said casing.

100

18. The combination of a conduit for the gaseous products resulting from the combustion of fuel, a casing, an electrical apparatus contained in said casing, and means to circulate gaseous products of combustion through said casing including means to connect said casing to said conduit at two points of gaseous pressure-difference therebetween.
